UNITED STATES PATENT OFFICE.

HENRY R. TOWNE, OF STAMFORD, CONNECTICUT, ASSIGNOR TO THE YALE & TOWNE MANUFACTURING COMPANY, OF SAME PLACE.

DESIGN FOR A LOCK OR LATCH CASE.

SPECIFICATION forming part of Design No. 25,150, dated February 11, 1896.

Application filed December 17, 1895. Serial No. 572,465. Term of patent 14 years.

To all whom it may concern:

Be it known that I, HENRY R. TOWNE, a citizen of the United States, and a resident of Stamford, in the county of Fairfield and State of Connecticut, have invented and produced a new and original Design for Lock or Latch Cases, of which the following is a specification, reference being had to the accompanying drawings, forming a part thereof, in which—

10 Figure I is a front elevation of a lock-ease, showing my design. Fig. II is a side view of the same. Fig. III is an end view thereof.

My design consists essentially of a lock having sides slightly inclined from the base to the 15 top, with a narrow marginal rim or flange extending along the two sides and rear at the bottom and a raised margin or bead on the top, inclosing a depressed panel.

The drawings clearly show my design, in 20 which are seen a lock-case and a corresponding strike or keeper. The sides and rear ends of both are slightly inclined from the base to

the top. The base consists of a narrow flange merging into the inclined side, and the latter terminates at the top with a raised margin or bead, which in turn incloses a depressed panel, 25 forming the top of the case or strike. The front of both the case and the strike is vertical, not inclined, and I prefer to make the upper edge of this front with a flat curve or arch, 30 as shown. Finally, I provide at the rear of the case and of the strike a boss or ear projecting beyond the marginal flange of the base and adapted to receive a screw.

Having thus described my invention, the 35 following is what I claim as new therein and desire to secure by Design Letters Patent:

The design for a lock or latch case; substantially as herein shown and described.

HENRY R. TOWNE.
